UNITED STATES PATENT OFFICE.

ROBERT H. AIKENS, OF WINNEMUCCA, NEVADA.

OIL BURNER.

Application filed May 31, 1927. Serial No. 195,416.

The present invention relates to an oil burner and has for its prime object to provide a construction wherein the oil is generated into a gas and mixed with air and then burned, the flame of the burning mixture being utilized to generate the gas from the oil.

Another very important object of the invention lies in the provision of a burner of this nature with which it is possible to have a small steady flame or a large flame or flames of any of the intermediate stages.

Another very important object of the invention lies in the provision of a burner of this nature which is practically silent in its operation.

A still further very important object of the invention resides in the provision of an oil burner of this nature having an exceedingly simple structure which may be manufactured at a low cost, is compact in its arrangement, convenient and easy to manipulate and adjust, thoroughly efficient and reliable in operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is fragmentary top plan view of one embodiment of the invention,

Figure 2 is a longitudinal vertical section therethrough, taken substantially on the line 2-2 of Figure 1,

Figure 3 is a transverse section taken substantially on the line 3-3 of Figure 2,

Figure 4 is an end elevation thereof,

Figure 5 is a top plan view of another embodiment of the invention,

Figure 6 is a vertical section taken substantially on the line 6-6 of Figure 7,

Figure 7 is a vertical section taken substantially on the line 7-7 of Figure 5,

Figure 8 is a fragmentary elevation showing the extremity of the air intake.

Referring to the drawing in detail, it will be seen that the embodiment of the invention shown in Figs. 1 to 4 inclusive is of a general rectangular formation, and this embodiment of the invention will be described in detail first merely by way of preference. The let-

ter R denotes a retort generator, the letter M denotes a mixing chamber and the letter B denotes the burner base. The base B comprises by way of preference, a rectangular bottom 5 having end walls 6 rising integrally therefrom. Flanges 7 rise from the sides of the bottom 5, extending longitudinally thereof and flanges 8 extending inwardly from the sides of the ends 6 being in the same vertical planes with flanges 7 and formed integrally therewith. Sides 9 are in the form of rectangular plates secured by suitable fastening elements 10 to the flanges 7 and 8. One end wall 6 is formed with a centrally located threaded opening 11 in which is threadedly engaged a needle valve structure 12 adjustable by a handle 13. This same end wall 6 is formed at its bottom with a series of air intake openings 14. The mixing chamber 10 comprises a bottom 15 having end walls 16 and side walls 17 rising integrally therefrom. The bottom 15 is formed with a continuous flange 18 adjacent its edge to be fastened to end walls 6 and the upper edges of the side plates 9 by suitable fastening elements 19. The bottom 15 is formed with a centrally located opening 20 into which one end of a gas and air intake pipe 21 extends. This pipe 21 is L-shaped and the long arm thereof is disposed horizontally and the shorter arm vertically, the terminal of the shorter arm extending into the opening 20 being held in place by means of a flange 22 formed integrally on said shorter arm and fastened to the bottom 15 by suitable fastening elements 23. The extremity of the longer arm of the intake pipe 21 is supported by means of a screw, bolt, or other fastening elements 24 threaded through an opening in the bottom 15. The extremity of the longer arm of the intake pipe 21 terminates adjacent and in spaced relation to the end wall 6 having the openings 14 and said longer arm is co-axially arranged in respect to the needle valve structure 12. The top plate of the mixing chamber M is denoted generally by the numeral 26 and along the median longitudinal dimension is formed with a depression 27 forming a well under the retort generator R while the remaining portions of the top plate 26 are perforated as is indicated at 28. The top plate 26 is held securely in place by means of screws, bolts, or other fastening elements 29 engaged in the bottom 15 as is more clearly illustrated

in Figure 3. A baffle structure is mounted on the top plate and comprises a vertically rising continuous wall 30 having an inwardly directed flange 31 between its upper and lower edges, adjacent the former to rest on the top plate as is clearly indicated in Figure 3.

The retort generator R is of an elongated cylindrical formation having closed ends and 10 is supported in the recess 27 longitudinally thereof by means of depending lugs 32 engaged with the bottom of the recess 27 by means of fastening elements 33. The recess is formed with rising walls 34 which brace 15 the retort generator R as is clearly illustrated in Figure 3, one on each side of the lugs 32. Baffle walls 35 depend downwardly from the sides of the recess portion of the top plate 26 into the mixing chamber as is 20 shown clearly in Figures 2 and 3. An oil pipe 36 is connected with one end of the retort chamber at the bottom thereof as is indicated at 37 and extends down through the mixing chamber into the burner base 25 and extends longitudinally through the burner base and through the end wall adjacent the needle valve structure 12. A pipe 38 leads from the other end of the retort generator adjacent the top thereof downwardly to the needle valve structure 12.

Attention is now directed to the circular embodiment of the invention disclosed in Figures 5 to 8 inclusive. In these figures the letter R' denotes the retort generator, 35 the letter M' the mixing chamber and the letter B' the burner base, corresponding respectively to the retort generator R, the mixing chamber M and the burner base B heretofore described in detail. The burner base 40 B' comprises a circular bottom 40 having a circular wall 41 rising therefrom adjacent its periphery. The mixing chamber M' comprises a bottom 42 of circular formation having a circular wall 43 rising from the 45 edge thereof. The center of the bottom 42 has an opening 44 from which depends an elbow tubular member 45 in the lower extremity of which is threaded a pipe 46 extending through an opening 47 in the side 50 wall 41 and terminating in a closed flared head 48 having an annular series of openings 49 and an annular series of openings 50 and a central opening 51 for receiving a 55 needle valve structure 52 adjustable by a handle 53. The bottom 42 is formed with an annular depending flange 54 inwardly spaced from its edge and extending inside of the upper edge of the wall 41 and secured thereto by means of fastening elements 55 or 60 in any other suitable manner. The top of the mixing chamber M' is in the form of a circular annular plate 56 having a circular depression 57 in the center thereof forming a well or recess from which depends an annular baffle flange 58 into the mixing chamber

M'. The retort R' is of cylindrical formation and its axis is disposed vertically. The lower end of the retort generator R' is reduced and externally threaded as is indicated by the numeral 59. This reduced end 70 is threadedly engaged in the top plate 56 by means of the inner wall 57' on the well 57. The remaining portion of the top plate 56 is perforated as is indicated at 60. This top plate is held in place by means of bolts 75 61 engaged in the bottom 42 outside of the wall 41. An annular baffle wall 62 is formed intermediate its top and bottom edges with an annular inwardly directed flange 63 resting on the top plate 60 while the lower portion of the baffle plate telescopes over the circular wall 43. An oil supply pipe 64 is engaged with the bottom of the retort generator R' and extends down through the elbow tubular structure 45 and radially 80 through the base B'. A pipe 65' rises vertically through the bottom of the retort generator R' terminating adjacent the upper end thereof and also a distance below the bottom thereof and is coupled with a pipe 90 66' extending radially through the mixing chamber and through the wall 43 and then bent downwardly terminating in engagement with the needle valve structure 52.

The retort generators R and R' are provided respectively with clean out plugs 65 and 66, the former in the end and the latter in the top of the respective retort generator. It is thought that the construction of the two embodiments will now be clearly understood without a more detailed description thereof. It will be seen that the parts are capable of easy assembly and disassembly and present a compact and convenient arrangement. These two embodiments have 100 been disclosed in detail merely by way of examples since in actual practice they attain the features of advantage enumerated as desirable in the statement of the invention and the above description as well as 105 the advantages which will be apparent from the description of the operation which is as follows:—

The retort generator R, R', must first be heated and this is accomplished by inserting 115 alcohol into the well formed by recess 27, 57, which is provided for this purpose. This alcohol is lighted and the burning thereof will cause the oil in the retort generator to be sufficiently heated for starting the generation of the gas through the pipe 38, 120 65—66, so that the needle valve structure will spray the oil into the pipe leading to the mixing chamber M, M'. The gas passing through these pipes will suck in sufficient air through the opening provided for this purpose as shown at 14 in the first embodiment and at 49 and 50 in the second embodiment. The mixture which will rise 125 through the apertures in the top of the 130

mixing chamber may be lighted by a match or torch just over the air check or baffle structure shown at 30 and 62 in the two embodiments. A small fire should be used for a short time and this will heat the retort generator sufficiently for a large fast fire. The generator must be very hot to operate the burner at slow speed. This burner has a very wide range of adjustment, a very small fire can be used or it can be increased to resemble a large blowtorch, the fire leaving the burner very forcibly. The fuel is fed to the burner from a tank (not shown) where a pressure of air is carried, this pressure of air forces the fuel to and through the burner through pipe 36, 64. The object in making the burner in a long and a round design is so that it can be used in round and long fireboxes or where a round or a long fire is required. Both burners use a large round retort generator. On the round burner, it will be noted, the generator is disposed in an upright or vertical position, while on the long burner the generator rests in a horizontal position. A strong draft or light wind will not interfere with the operation of these burners while being used in the open. The burners produce a very intense heat and a clean blue blaze and create very little noise while in operation. The baffle or shields shown at 30 and 62 in the respective embodiments of the invention shown prevent a side draft which would tend to blow out the flame at the periphery 25 of the plates 26 and 56 respectively.

It is apparent that changes in the details of construction, and in the combination and arrangement of parts may be resorted to without departing from the spirit or scope 40 of the invention as hereinafter claimed or sacrificing any of its advantages.

Having thus described my invention, what I claim as new is:—

1. A burner of the class described comprising a base structure, a mixing chamber, and a retort generator, said base structure comprising a bottom with end walls rising therefrom, flanges projecting inwardly from the bottom and end walls, side plates fixed 45 to said flanges, a needle valve structure mounted in one of the end walls, said mixing chamber comprising a bottom having a depending flange adjacent the periphery thereof, means fixing the last mentioned flange 50 to the ends of the base structure and the side plates thereof, a wall arising from the bottom of the mixing chamber, a top resting on the wall of the mixing chamber, a portion 55 of the top having formed therein a depression to form a well and the remaining portion being perforated, a retort generator 60 mounted on the top plate above the depression, a pipe connecting the retort generator with the needle valve structure, an intake 65 pipe leading from the bottom of the mixing

chamber through the base structure terminating co-axially and in spaced relation with the needle valve structure, said end wall of the base structure having mounted therein the needle valve structure being provided 70 with openings.

2. A burner of the class described comprising a base structure, a mixing chamber above the base structure, and a retort generator above the mixing chamber; said base structure comprising a circular bottom having an annular wall rising therefrom, said mixing chamber comprising a circular bottom having an annular wall rising therefrom, the bottom of the mixing chamber having an 75 annular flange depending therefrom and fixed to the upper edge of the wall of the base structure, an elbow tube depending from the center of the bottom of the mixing chamber, a pipe connected therewith extending radially through the base structure through 80 an opening in the wall thereof and terminating exteriorly in an enlarged hollow head having air intake openings, a needle valve structure mounted in the head, said retort generator being of cylindrical formation, said mixing chamber having a perforated top plate formed with a depression having an opening in which the retort generator is threaded engaged, a pipe leading 85 from the retort generator to the needle valve structure.

3. A burner of the class described comprising a base structure, a mixing chamber above the base structure, and a retort generator above the mixing chamber; said base structure comprising a circular bottom having an annular wall rising therefrom, said mixing chamber comprising a circular bottom having an annular wall rising therefrom, the bottom of the mixing chamber having an 90 annular flange depending therefrom, and fixed to the upper edge of the wall of the base structure, an elbow tube depending from the center of the bottom of the mixing chamber, a pipe connected therewith extending radially through the base structure through 95 an opening in the wall thereof and terminating exteriorly in an enlarged hollow head having air intake openings, a needle valve structure mounted in the head, said retort generator being of cylindrical formation, said mixing chamber having a perforated top plate formed with a depression having an opening in which the retort generator is threaded engaged, a pipe leading 100 from the retort generator to the needle valve structure.

4. A burner of the class described comprising a base structure, a mixing chamber, and a retort generator; said base structure comprising a bottom with a wall structure 105

110

115

120

125

130

rising therefrom, a needle valve structure mounted in the wall structure; said mixing chamber comprising a bottom having a depending flange adjacent the periphery thereof, means fixing the flange to said wall structure, a wall rising from the bottom of the mixing chamber, a top resting on the wall of the mixing chamber, a portion of the top having formed therein a depression to form a well and the remaining portion being perforated, a retort generator mounted on the

top above the depression, a pipe connecting the retort generator with the needle valve structure, an intake pipe leading from the bottom of the mixing chamber through the base structure and terminating coaxially and in spaced relation with the needle valve structure. 15

In testimony whereof I affix my signature.

ROBERT H. AIKENS.
